(57) **CLAIM**

I claim the ornamental design for a power ratchet wrench, as shown and described.

DESCRIPTION

FIG. 1 is a perspective view of a power ratchet wrench.

FIG. 2 is a left side view of the power ratchet wrench.

FIG. 3 is a right side view of the power ratchet wrench.

FIG. 4 is a top view of the power ratchet wrench.

FIG. 5 is a bottom view of the power ratchet wrench.

FIG. 6 is a front view of the power ratchet wrench; and,

FIG. 7 is a rear view of the power ratchet wrench.

The broken line showing of portions of the power ratchet wrench form no part of the claimed design.
